UNITED STATES PATENT OFFICE.

DE VER H. WARNER, OF BRIDGEPORT, CONNECTICUT.

DESIGN FOR A DRESS-STAY.

SPECIFICATION forming part of Design No. 22,283, dated March 14, 1893.

Application filed January 3, 1893. Serial No. 457,161. Term of patent 7 years.

To all whom it may concern:

Be it known that I, DE VER H. WARNER, a citizen of the United States, residing at Bridgeport, Fairfield county, State of Connecticut, have invented certain new and useful Improvements in Designs for Dress Stays, of which the following is a specification.

My invention is a design for dress stays embodying the features hereinafter more particularly set forth.

In the accompanying drawing I have shown a perspective view of a dress stay embodying my design.

The design embodies a stay A, the edges of which are of irregular contour being shown substantially tooth-shaped, as at a, and extending substantially the length of the stay is a double line of stitching b, the lines being connected at their ends as at b'. Arranged

between the lines of stitching and the irregular edges of the stay are a series of openings c, giving the appearance of dots.

The essential features of the design consist in the stay having an irregular or serrated contour with the rows or series of openings or dots on its surface corresponding substantially to the general contour of the stay.

What I claim is—

The design for a dress stay, substantially as herein shown and described.

In testimony whereof I have signed my name to this specification in the presence of two subscribing witnesses.

DE VER H. WARNER.

Witnesses:

FRANK S. ANDREWS,
M. M. WHEATON.
